COMBINED LAMP HOUSING AND STAND

Dieter Rams, Konigstein, Taunus, Germany, assignor to
Braun Aktiengesellschaft, Frankfurt am Main, Germany

Filed Aug. 18, 1964, Ser. No. 81,354

Claims priority, application Germany Feb. 21, 1964

Term of patent 14 years

(Cl. D48—20)

FIG. 1

FIG. 2

FIG. 3

FIG. 4

FIG. 5

FIG. 6

FIG. 1 is a top left hand perspective view of a combined lamp housing and stand embodying my new design;

FIG. 2 is a top right hand perspective view thereof embodying my new design;

FIG. 3 is a top plan view thereof embodying my new design on a somewhat smaller scale than indicated in FIGS. 1 and 2;

FIG. 4 is a bottom plan view thereof embodying my new design on the same scale as FIG. 3;

FIG. 5 is a right side perspective view with the lamp oriented in an operating position, embodying my new design, the left perspective view of the lamp being substantially identical therewith; and

FIG. 6 is a front elevational view thereof embodying my new design on a somewhat smaller scale than indicated in the other figures.

I claim:

The ornamental design for a combined lamp housing and stand, as shown and described.
